ELECTRICAL CONNECTOR

Anna A. Jochum, Indianapolis, and John Frank
Michener, Carmel, Ind.

Application November 13, 1941, Serial No. 418,978

1 Claim. (Cl. 173—343)

The present invention relates to new and useful improvements in electrical connectors, and has for its primary object to provide, in a manner as hereinafter set forth, a device of this character comprising male and female members of a novel construction and arrangement whereby the connection may be expeditiously made without the necessity of holding the male member in a certain predetermined position prior to its insertion.

Another very important object of the invention is to provide an electrical connector of the aforementioned character which includes unique means for detachably securing the male and female members together.

Other objects of the invention are to provide an electrical connector of the character described which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in vertical section through an electrical connector constructed in accordance with the present invention.

Figure 2 is a view in horizontal section, taken substantially on the line 2—2 of Figure 1.

Figure 3 is a view in horizontal section, taken substantially on the line 3—3 of Figure 1.

Figure 4 is a detail view in elevation of the male member.

Referring to the drawing in detail, it will be seen that the embodiment of the invention which has been illustrated comprises complementary male and female members 1 and 2, respectively, of suitable insulating material.

The female member 2 comprises a plug 3 having on one end portion a suitable screw shell 4 of metal. It may be well to here state that the female member 2 is adapted to be screwed into a conventional threaded socket or receptacle.

The plug 3 has formed centrally therein and extending from end to end thereof a bore 5. Embedded in the plug 3 at an intermediate point is a snap ring 6. The ring 6 is electrically connected at 7 to the shell 4. The ring 6 includes integral gripping elements 8 which project into the bore 5 of the plug 3. A substantially V-

shaped circular groove 23 in the wall of the bore 5 accommodates the resilient elements 8 and permits flexing thereof in opposite direction.

The male member 1 includes a prong 9 which projects from a head 10. The prong 9 is engageable in the bore 5 of the plug 3 and said prong is of sufficient length to extend entirely through said plug and project therefrom. At an intermediate point the prong 9 has mounted thereon a collector ring 11 of substantially concave cross-section in which the elements 8 of the ring 6 are engageable. This is shown to advantage in Figure 1 of the drawing.

Depending from the head 10 is an integral, circular neck 12 which is engageable on one end of the plug 3. The neck 12 is spaced concentrically from the prong 9 and, in conjunction therewith, defines an annular channel 13 beneath the head 10. Extending into the head 10 from the top thereof is a socket 14. Diverging passages 15 establish communication between the socket 14 and the channel 13.

On the free end of the prong 9 is a contact 16. A conductor 17 in the prong 9 has one end connected to the contact 16 and its other end secured by a screw 18 in the channel 13 of the head 10. A conductor 19 has one end electrically connected to the collector ring 11 and its other end secured in the channel 13 by a screw 20.

The socket 14 accommodates an end portion of an extension cord 21. The conductor wires 22 of the extension cord 21 are inserted through the passages 15 and electrically connected with the conductors 17 and 19 by the screws 18 and 20.

It is thought that the manner in which the device functions will be readily apparent from a consideration of the foregoing. Briefly, the prong 9 is inserted in the bore 5 of the plug 3 and projected through and beyond said plug, the neck 12 engaging one end thereof. The resilient elements 8 of the ring 6 snap into the substantially concave collector ring 11 for releasably securing the male and female members together and for providing a good electrical connection therebetween. When the plug 3 is screwed into an electrical receptacle the element 16 functions as the base contact of the connection.

It is believed that the many advantages of an electrical connector constructed in accordance with the present invention will be readily understood, and although a preferred embodiment of the device is as illustrated and described, it is to be understood that changes in the details of construction and in the combination and arrange-

ment of parts may be resorted to which will fall within the scope of the invention as claimed.

What is claimed is:

An electrical connector comprising a female member having a bore therein for the reception of a male member, said female member further having a substantially V-shaped, circular groove at an intermediate point in the wall of the bore, a metallic screw shell mounted on one end por-

tion of the female member, and a snap ring embedded in the female member at an intermediate point and electrically connected to the shell, said snap ring including inwardly extending resilient elements projecting into the bore for engagement with the male member and adapted to flex in opposite directions in the groove.

ANNA A. JOCHUM.
JOHN F. MICHENER.
